UNITED STATES PATENT OFFICE.

CHARLES AUGUSTUS SHIVELY, OF HOQUIAM, WASHINGTON.

GRATE CONSTRUCTION.

Application filed September 25, 1920. Serial No. 412,063.

To all whom it may concern:

Be it known that I, CHARLES A. SHIVELY, a citizen of the United States, and a resident of Hoquiam, Grays Harbor County, 5 State of Washington, have invented a new and useful Improvement in Grate Constructions, of which the following is a full, clear, and exact description.

My invention relates to improvements in grate constructions, and it consists in the combinations, constructions and arrangements herein described and claimed.

An object of my invention is to provide a grate construction for boiler furnaces and the like that is so formed and arranged that the bearing bars therein may expand or contract longitudinally or transversely or become distorted on account of the action of heat, weight, or other cause without injuring the supporting walls of the device or rendering the device unserviceable.

A further object of my invention is to provide in a device of the type described a novel form of bearing bar that can be rotated 180° when distorted by sagging downwardly to reverse the upper and lower surfaces thereof, wherefore the normal strain placed upon the reversed bearing bar will tend to straighten the same.

30 A further object of my invention is to provide in a device of the type described a bearing bar that on account of its novel construction can be used longer in service than any bearing bar heretofore provided.

35 A further object of my invention is to provide a device of the type described that can be manufactured cheaply, is not likely to get out of order easily, and is thoroughly practical commercially.

40 Other objects and advantages will appear in the following specification, and the novel features of the invention will be particularly pointed out in the appended claims.

45 My invention is illustrated in the accompanying drawings, forming part of this application, in which—

Fig. 1 is a plan view of a bearing bar used in my device showing the method of supporting the same at its middle,

50 Fig. 2 is a side view of the portion of the device shown in Fig. 1,

Fig. 3 is an end view of a bearing bar shown in Fig. 1,

55 Fig. 4 is a section along the line 4—4 of Fig. 2,

Fig. 5 is a vertical section through a frag-

mentary portion of a furnace equipped with my improved grate construction, showing the method of supporting a bearing bar at the end thereof,

60 Fig. 6 is a front view of a bearing box embodied in the device,

Fig. 7 is a section along the line 7—7 of Fig. 5,

Bearing bars ordinarily provided for supporting grate bars and other weights under steam boilers and in furnaces of various kinds will in service sag at their middle points on account of the strain placed thereon and will expand and contract on account 70 of thermal changes. It has been the common practice in constructing furnaces to fix the ends thereof rigidly in the side walls of the furnace. Consequently, when the bearing bars sag at their middle portions or expand and contact, the side walls of the furnace surrounding the ends of the bearing bars are impaired since the fire brick and lining composing the side walls will be dislodged by the movement of the bearing 80 bars.

When my improved grate construction is incorporated in a furnace for boilers and the like, the bearing bars may expand, contract, and sag or become otherwise distorted without in any way injuring the walls of the furnace. In addition, the bearing bars may be removed and others substituted therefor without it being necessary to change the wall construction in any way.

90 Referring now to the drawings, 1 denotes a side wall of a furnace in which my invention is carried out. The side wall 1 which is otherwise ordinary in construction is formed with a recess 2 adapted to receive a bearing box 3 that has its top and front sides open as shown and is provided with a fin 4 projecting exteriorly from its under surface into a recess 5 in the wall to maintain the box in the position shown in Fig. 100 5. It will be noted that the front edge of the wall box does not extend flush with the edge of the recess 2. It will be understood that a second side wall (not shown) will be positioned opposite the wall 1 and will be 105 constructed in a precisely identical manner.

I then provide precisely identical longitudinal bearing bars indicated in general at A and B, each of which comprises a body portion 6 formed with a neck 7 and a head 110 8 at one end thereof as shown. The head 8 has its rim edge slightly convexed or

curved outwardly at 9 so as to provide a spherical surface.

The body portion 6, which in the form of the device now preferred by me, is substantially square in cross-section, may have a cross section of any desired form, it only being essential to my invention that two or more diametrically opposed surfaces thereof be fashioned to engage with the ends 10 of a plurality of grate bars 10. Referring now particularly to Figures 1 and 2, it will be noted that each of the body portions 6 is provided with longitudinally alined apertures 11 and 12, thereby defining spacing 15 members 11' between parallel side members. Similar integral spaced apart parallel longitudinal ribs 13 and 14 project upwardly from the upper surface of each of the body portions 6 while precisely identical ribs 15 and 16 depend from the lower or opposite surfaces thereof. As best seen in Fig. 7, the spaced apart ends of alined grate bars 10 rest upon and are supported by each of the body portions 6. The grate bars 10 are 20 disposed transversely to the bearing bars and the ribs 13 and 14 of the latter are arranged to enter recesses 17 and 18, respectively, in the grate bars to prevent displacement of the same. The grate bars 10 are 25 otherwise ordinary in construction and therefore require no detailed description.

From the foregoing description of the various parts of the device, the operation thereof may be readily understood. The bearing bars A and B are arranged in horizontal alinement between the side walls of the furnace, the heads 8 being positioned within opposite bearing boxes 3. The relative dimensions of the bearing box 3 and 35 the head 8 are such that spaces are provided between the rear interior wall of the bearing box 3 and the adjacent portion of the head 8 and between the upper wall of the recess 2 and the rim edge of the head 9. The adjacent ends of the bars A and B rest 40 upon a substantially semi-cylindrical saddle 19 carried by an upright support 20 that is positioned intermediate the side walls of the furnace and is provided with an air passage 45 21. The adjacent ends of the bars A and B are spaced apart to permit the circulation of air therebetween.

It is obvious that two bearing bars A and B may be formed integrally where the distance between the side walls of the furnace 55 is not sufficient to necessitate the provision of the intermediate support 20. Any desired number of the bearing bars may be provided, the number being determined by 60 the area of the furnace. These bearing bars are positioned parallel with respect to each other and support rows of spaced apart grate bars 10 which are disposed transversely thereto. Air circulates through the

air passages 11 and 12 and between the adjacent ends of the grate bars 10, thereby cooling the same. In service, the bearing bars will of course be heated and will expand longitudinally and transversely. The expansion of the bearing bars and the subsequent contraction when cooled is permitted without injury to the wall of the furnace since ample space for the movements of the heads of the bearing bars in their respective bearing boxes is provided, as has been hereinbefore pointed out. The bearing bars support heavy loads and in service gradually sag at points intermediate their supports. On account of the curved peripheral surfaces of the heads of each bearing bar as described, the sagging of the bar intermediate its length will cause the heads thereof to roll slightly in the direction of the sagging portion of the bar. Consequently, the only distortion in the bar will be at the point of sagging. When the bearing has sagged sufficiently to warrant the operation, the grate bars supported thereby are jacked up and the upper and lower surfaces of the bearing bar are reversed. Thereupon the strain upon the bearing bar that caused the sagging will now tend to straighten the same before any further sagging results. The bearing bars may be reversed many times and the period of service thereof be thereby greatly extended beyond the life of an ordinary bearing bar.

If desired, the spaces between the adjacent walls of each of the bearing boxes 3 and the head and neck of the bearing bar disposed therein may be filled with a suitable flexible material 22 that is a non-conductor of heat, such as asbestos. This material will be held in the position shown by the engagement thereof with the walls of a groove 23 that is provided in the interior wall of the bearing box.

I claim:

1. In a grate construction, a bearing bar consisting of a body portion having a head at one end thereof and a relatively reduced neck portion disposed between the body portion and the head, said body portion being formed with opposite side members thereof parallel and with an elongated opening therethrough extending between the parallel side members.

2. In a grate construction, a bearing bar consisting of a body portion having a head at one end thereof and a relatively reduced neck portion disposed between the body portion and the head, said body portion being formed with opposite side members thereof parallel, with an elongated opening therethrough extending between the parallel side members, and with an integral longitudinal rib projecting vertically from the upper and

lower surface of each side member, the head being adapted to form a supporting surface for one end of the bar.

3. A grate construction comprising a bearing bar consisting of a body portion having a head at one end thereof, said head being fashioned with a spherical-shaped outer rim, said body portion being formed with parallel side members spaced apart and each provided with a longitudinal rib on its upper and with a longitudinal rib on its lower surface, means for supporting the head of the bar to permit rotation of the bar, and means for supporting the bar at its opposite end.
- 15 4. A grate construction comprising a bearing bar consisting of a body portion having a head at one end thereof, said head being fashioned with a spherical-shaped outer rim, said body portion being formed with parallel side members spaced apart and each provided with a longitudinal rib on its upper and with a longitudinal rib on its lower surface, means for supporting the head of the bar to permit rotation of the bar, and a
- 20 25 grate bar having a notch in its under surface adapted to receive a rib on the upper surface of the bearing bar.

5. A bar for supporting grate bars, said

bar having parallel spaced apart side members, integral spacing members disposed between said side members, and a head and neck portion forming an integral part of said bar, said head being provided with a spherical-shaped peripheral surface, each side member being provided with a longitudinal rib on its upper and with a longitudinal rib on its lower surface.

6. A grate construction comprising a wall, a bearing box carried by said wall, a bar having spaced apart parallel side members and a spherical-shaped head, each side member being provided with a longitudinal rib on its upper and with a longitudinal rib on its lower surface, said bar having a reduced integral portion positioned between said head and said side members, said head adapted to be supported by said bearing box, said head being movable longitudinally and laterally with respect to said box, a non-conducting material carried by said box and disposed around said reduced portion, a concave saddle supporting the other end of said bar, and grate bars having notches adapted to receive said ribs.

CHARLES AUGUSTUS SHIVELY.
